EDGE ILLUMINATED SIGN

Paul E. Fuchs, Colorado Springs, Colo.

Application August 5, 1948, Serial No. 42,703

1 Claim. (Cl. 40—130)

1

My invention pertains to signs, and relates more particularly to signs of the edge-illuminated type such as those formed from acrylic resins. This application is related to my co-pending application, Serial No. 32,909, filed June 14, 1948.

One of the principal objects of my invention is to provide an edge-illuminated sign in which a plurality of light-transmitting plastic plates of relatively large dimensions, each bearing an engraved legend, may be uniformly illuminated at high intensity with light of similar or contrasting colors.

Other objects of my invention include the provision of improved methods and devices for sealing the edges of such signs against the entry of foreign material, for engraving legends on the signs in such manner that the size of the legend appears uniform to the eye regardless of variations in the intensity of illumination and for assembling composite signs in an efficient, inexpensive, and durable manner.

Further objects of my invention include the provision of an engraving guide which is of material assistance to an operator in forming the legend on such signs.

Additional objects of my invention, pertaining to the diverse novel formations and arrangements of parts and to the various methods employed, will be disclosed in the course of the following description taken in conjunction with the appended drawings in which:

Fig. 1 is an elevation of an edge illuminated sign incorporating my invention;

Fig. 2 is a partial front elevational view, partly broken away, of the central portion of the sign shown in Fig. 1;

Fig. 3 is a plan view of a lamp assembly and housing for use with my sign;

Fig. 4 is a cross section taken along the lines 4—4 in Fig. 2;

Fig. 5 is a fragmentary section corresponding to the fragmentary sections shown in Fig. 4 and positioned at 90° to the showing in Fig. 4, illustrating the application of a backing plate to the upper plate;

Fig. 6 is a fragmentary section corresponding to the fragmentary sections shown in Fig. 4 and positioned at 90° to the showing in Fig. 4, illustrating the use of a reflective strip and plastic members in association with the upper plate;

Fig. 7 is a view similar to Fig. 6, illustrating a modified form of reflective strip and plastic members in association with the upper plate;

Fig. 8 is an elevation of a modified form of my sign;

2

Fig. 9 is a fragmentary cross-sectional view, on an enlarged scale, of a modified form of structure taken approximately in a position corresponding to line 9—9 of Fig. 8;

Fig. 10 is a view similar to Fig. 9 but illustrating a somewhat further modified form of structure;

Fig. 11 is a sectional view of a modified form of strip used in the fashion of the strip shown in Fig. 10;

Fig. 12 is a view similar to Fig. 11 and illustrating a further modified form of strip;

Fig. 13 is a plan view of an engraving guide;

Fig. 14 is a cross section taken along the line 14—14 of Fig. 13;

Fig. 14A is a plan view of the strip shown in Fig. 14;

Fig. 15 is an elevation of a series of engraving guides arranged on a suitable backing plate;

Fig. 16 is an edge elevational view of a tool for use with my engraving guide;

Fig. 16A is a front elevational view of the tool shown in Fig. 16;

Fig. 17 is an elevational view of another tool for use with my engraving guide;

Fig. 18 is a fragmentary cross-section of the plate 21 shown in Fig. 4, employing my improved form of engraving and drawn to an enlarged scale;

Fig. 19 is an elevation of a suitable tool for engraving my sign;

Fig. 20 is an end view of the tool shown in Fig. 19;

Fig. 21 is an elevation of a tool shown in Figs. 19 and 20;

Fig. 22 is a partial plan view of a modified form of plate for my sign;

Fig. 23 is a partial plan view of a modified engraving; and

Fig. 24 is a cross section taken along the line 24—24 of Fig. 23.

Edge-illuminated signs formed from sheets or plates of a plastic such as the hard acrylic resins have been known for several years and utilized the unusual light-transmitting characteristics of such materials to convey light from a suitable source through an edge of the plate to an engraved legend or indicia formed in the plate. In conventional signs of this nature a great proportion of the light entering the sign is intercepted by the portions of the legend disposed closest to the source of illumination, creating a sometimes pleasing highlight effect to these portions, but leaving the remainder of the legend very dimly illuminated. This characteristic, plus the inev-

itable loss of light in transmission and edge radiation has limited both the maximum size and use of such signs.

I have found these and other undesirable effects can be largely overcome and the maximum over-all size of the sign substantially increased by disposing a lamp or other suitable source of illumination between especially formed edges of light-transmitting plastic plates, which form in combination a complete sign. The edges nearest the source of illumination are formed to diffract the incident light rays entering the plate in a plane parallel to the plane of the plate, and reflective surfaces are provided on the other edges of the sign to reflect light into the plate which would otherwise be lost. As a result, substantially all of the light entering the edges of the plate is used for the illumination of the legend and yields a substantially uniform degree of illumination having remarkable brilliance.

Because of the position of the source of illumination with respect to the legend, and also because of the reflective edges and formed edges, I am able to adequately illuminate a much larger area than has heretofore been considered practical in edge illuminated signs.

A backing plate 20 may be mounted in contact with the back or engraved surface of the plates 21 and 22 to intensify or vary the appearance of the legend 53. If the sign is to be continuously illuminated, the plate 20 may be of opaque material of any desired color, whereas if illuminated only on occasion, translucent or transparent plates 20 may be provided. The contrast thus obtained, particularly with colored opaque or translucent sheets 20 is striking, and increases the flexibility of my sign.

I may also apply a suitable dye of any desired color to all or any portion of either the face or back of the plates 21 and 22, or in certain instances, a paint may be substituted for the dye. Usually, a dye applied evenly to the face of the sign is the most effective, and eliminates the need for colored sheets or plates.

Since the high brilliance of the legend obtained in my signs under artificial illumination imparts to the legend formed in the plate an apparently greater size as compared to the same legend when illuminated only by daylight, I provide a special rotating tool for forming or engraving a new and improved form of legend, in which the apparent increase in size due to the high brilliancy is largely compensated. This I accomplish by forming a relatively shallow but wide groove or trough superposed on the conventional trough-shaped engraving, with the result that the deeper portions of the engraving intercept the major quantity of the light rays entering the edge from an artificial source, but the full width of the shallow groove is visible under daylight illumination, particularly when viewed from the front of the sign.

As an aid in forming the engraved legend, I provide flexible strips of a pressure sensitive adhesive material having a non-adhesive surface, preferably grooved to receive the guide pin or tracing member of a pantograph or engraving machine. The legend or indicia may be formed from these flexible strips by arranging the strips in the desired manner on a suitable support and subsequently following the groove in the strips to reproduce the legend on the plate. If an error is made in laying out the legend with the flexible strips, correction is a simple matter due to the use of a pressure sensitive adhesive material.

For more detailed description, reference is made to Fig. 1 in which I have illustrated a simple form of sign incorporating my invention. My sign comprises an upper plate 21 and a lower plate 22 spaced apart a distance sufficient to receive a suitable tubular lamp 23. The plates 21 and 22, which may be on the order of three-eighths to one-half inch in thickness are formed of an acrylic resin such as methyl methacrylate or cyclohexyl methacrylate and possessing the characteristic of transmitting light from edge to edge parallel to the plane of the sheet in addition to transmitting light from face to face in the manner of ordinary transparent materials, this characteristic being herein termed "light-transmitting" as contrasted with transparent.

The edge of each of the plates 21 and 22 selected for disposition near the lamp 23 is provided with a series of flutings or scallops 24, shaped in such manner as to cause a diffraction of the light rays entering the plate through the fluted edge in a plane generally parallel to the plane of the plate. The scallops 24 may therefore resemble portions of a right cylinder having its axis perpendicular to the plane of the plates or other similar shapes.

The lamp 23 is preferably of the hot cathode fluorescent type adapted to operate without the generation of appreciable quantities of heat, thus permitting placement of the lamp in close proximity to the edges of the plates 21 and 22. I also prefer to select a lamp having a diameter approaching the thickness of the plates to avoid waste of the light emitted by the lamp.

Lamp sockets 26 of conventional design are mounted in a trough-like metal housing 27 having side flanges 28 and end flanges 29. The height of the side flanges 28, plus the width of the housing 27 should be sufficient to overlap the scallops 24 formed on the opposed edges of the plates 21 and 22, when secured to the back of the sign. A suitable ballast and/or reactor 31 may be mounted on the housing 27 or disposed in other convenient location. A cover 32 having end flanges 33 and side flanges 34 in the same plane is secured to the face of the sign and is provided with a raised central portion 36 dimensioned to fit over the lamp 23 and sockets 26. The over all width of the cover 34 is similar to the over all width of the housing 27 and is mounted on the sign in alignment with the housing by suitable bolts 37 extending through the cover 32 and the housing 27. The plates 21 and 22 are preferably somewhat longer than the over all length of the lamp 23 and the sockets 26. I therefore provide opaque spacers 38 for disposition between the end flanges 33 and 29 to prevent the undesirable transmission of light between the plates 21 and 22.

The spacers 38 may be provided with a suitable opening 39 to permit passage of the bolt 37, and may also have reflective surfaces 41 in contact with the edges of the plates 21 and 22. Suitable edging 42 extends around the external edges of the assembled sign and fits closely to the plates 21 and 22, preferably overlapping the end flanges 33 and 29. Corner plates 43 having aligned openings for bolts 44 are provided on each of the corners for holding the sign and edging 42 in assembled position, the lower corner plates being provided with feet 46, if desired.

For indoor use, the edging 42 may suitably be of aluminum or similar material having a highly reflective internal surface in contact with the edge of the plates, the object of this structure

being to reflect back into the sign light which would otherwise escape through the exposed edges. If, however, the sign is to be exposed to the weather or dusty conditions, I prefer to employ a structure of the type illustrated in Figs. 6 and 7. As shown in Fig. 6, I may secure a strip 47 of material having a highly reflective surface on the edge of the plate 21 by plastic members 48 having laterally extending sections 49 engaging the strip 47. The members 48 may be sealed to the plastic plates 21 or 22 by the suitable application of heat, solvents, or adhesives, thus providing a water-proof and dust-tight seal for the edges.

As illustrated in Fig. 7, members 51 may be provided with aligned grooves 52 to receive the edges of the strip 47 and secured to the plates 21 in similar manner.

A legend or indicia 53 may be formed on the plates 21 and 22 by engraving the rear surface of the plates. The trough or groove formed by engraving may be either U-shaped or V-shaped and ordinarily should not be of a depth greater than half the depth of the plates 21 or 22. Although I may use conventional engraving of the type described, I prefer to employ engraving of the type illustrated in Fig. 18, wherein I provide a U-shaped or a V-shaped groove 54 formed in the rear surface of the plate and preferably extending not more than half way into the plate 21. Near the rear surface of the plate 21 I form a superposed countersunk or enlarged portion 56 over the groove 54, which is very shallow, but extends laterally in both directions beyond the extremities of the groove 54. A groove of this nature may best be formed by employing a tool of the type illustrated in Figs. 19 and 20 having a shank 57 and a head 58. An axially disposed crest 59 is formed on the extremity of the head 58, which is preferably flattened as indicated in Fig. 19. One side of the head 58 extends outwardly as at 60, terminating in a shoulder 62 normal to the axis of the tool. The face 63 of the tool defined by the relatively flat surfaces of the shoulder 62 and the sloping portion extending to the shoulder from the crest 59 may be inclined at a slight angle to form a cutting edge. The tool may be mounted by the shank 57 in a suitable engraver or otherwise rotated to form the desired type of engraving. As applied to the plate, it may be seen that the crest 59 of the tool forms the basis of the groove 54, while the shoulder 62 engravess the counter-sunk portion 56.

Light traveling through the plate 21 parallel to the faces will be intercepted primarily by the groove 54, which extends into the plate 21 a substantial distance. The counter-sunk portion 56, being shallow, will intercept only a minor portion of this light but will be visible when viewed from the front surface of the sign under even poor illumination. Thus the effect of increase in size of the legend due to the high brilliance imparted to the groove 54 is largely compensated by the addition of the surrounding counter-sunk portion 56, which is more dimly illuminated, and the legend will appear approximately the same dimensions regardless of the intensity of illumination.

It is possible to obtain a great number of varied and pleasing color effects with my sign through the proper application of transparent colored films of material. For example, a central portion 36 of the cover 32 may be provided with one or more slits 64. A channel-shaped, transparent, colored plastic channel 66 having a web 67 and

sides 68 may be fitted over the lamp 23 and held in place either by suitable clips or by the natural resiliency of the material. The channel 66 may be of uniform color, in which instance the legend on the plate 21, the legend on the plate 22, and the slits 64 will all be illuminated with the same color. If different colors are desired, each of the sides 68 may be of different color, while a third color may be employed on the web 67. It is not of course necessary that the colored transparent member be formed in the shape of a channel, since strips may be suitably supported on or near the edges of the plates 21 and 22 for this purpose.

15 I may also indent sections of the central portion 36, as indicated at 69, to receive a flat strip 71 of transparent colored material, or a strip 72 having a curved portion 73 projecting into the slit 64. Alternatively, a strip 74 may be masked in part by strip 76 of opaque or translucent material to define a somewhat narrower visible portion, see Fig. 12. Similarly, the strip 76 may be applied to strip 72 as indicated in Fig. 11.

It will be understood that the legends of signs must be ordinarily spaced to provide a balanced and pleasing effect to the assembly, and that I may dispose the lamp or lamps 23 in any one or more of these spaces. The same lamp, therefore, in most instances contributes at least a portion of its light to two plastic sheets, rather than to one, as in conventional signs, with the result that the distance between lamps can be at least doubled without sacrifice of brilliance. Any desired number of sheets or plates may therefore be employed edgewise to the lamp or lamps 23. To illustrate further this application of my invention, I have shown in Fig. 8 a relatively large sign comprising a plate 76 bearing a legend 77 engraved on its rear face. Covers 78, similar to cover 32, are mounted over lamps disposed along the upper and lower edges of the plate 76, these edges being provided with scallops 24 as previously described. Relatively long and narrow plastic plates 79 may be secured in position on the outer sides of the lamps in opposed relation to the plate 76 by suitable edge channels 81 and also provided with engraving 82. Corner plates 83, similar to those previously described, may be employed to lock the sign together. As the lamps are illuminated, it will be seen that both plate 76 and the plate 79 will be illuminated and that the light from each of the lamps need penetrate the plate 76 for only half of its height. The plate 76 may therefore have a height at least twice as great as that which would otherwise be permissible for the same intensity of illumination.

Difficulty is often encountered in obtaining the proper configuration of the legend of the sign regardless of the type of engraving tool or pantograph employed. I have found that this difficulty can be largely overcome through the use of flexible strips of material 76 having a flat lower surface 86 coated with a pressure sensitive adhesive. The upper surface 87 is preferably of a smooth non-adhesive character and may be provided with a longitudinal groove 88 in which the guiding pin of a pantograph or engraving machine may be placed. Strips of this material may therefore be applied to a suitable backing 89 and bent as desired to form the legend. Relatively straight strips such as those indicated in Fig. 13 may be applied to the backing 89, see Fig. 15, in combination to form angular letters, the grooves 88 in each of the strips being connected as at 90 by appropriate use of a suitable

tool such as that indicated in Fig. 16. This tool comprises a shank 94 having a wedge-shaped head 97 by means of which a portion of the strip 84 may be depressed to connect the groove 88 with a similar groove in another strip. A pointed tool 96 may also be employed. Once the strips 84 have been properly arranged on the backing 89, it is a simple matter for an engraver to follow the grooves 88 to reproduce in either an enlarged or reduced form the desired legend. Errors occurring in the placing of the strips 84 are easily corrected, since the strip 84 may be lifted from the backing 89 and reapplied in a corrected position without disturbing other portions of the legend. Once formed, the engraver may retain the backing 89 with the legend applied for future use or may remove the strips 84 from the backing 89 for subsequent use in the formation of other legends.

It is not essential that the precise edge configuration illustrated at 24, Fig. 2, be applied to obtain a satisfactory dispersion of light. I may, for example, substitute an edge configuration similar to that illustrated in Fig. 22, wherein the edges of plate 21' are serrated as at 93-93' to form intersecting edge portions preferably at approximately ninety degrees. Thus the light entering one edge passes in a straight line through the plate 21' and is reinforced by light entering from a corresponding opposed edge portion on the opposite edge. The reinforcing of the light rays obtained by this modification is particularly helpful in large signs since the rays from each illuminated edge reinforce in a criss cross pattern corresponding rays entering from the opposite edge.

It is in some instances desirable to increase the width of the letters or numerals constituting the legend without increasing the thickness of the plate 21. This I accomplish by forming the various segments of lines making up the legend in the manner illustrated in the Figs. 23 and 24, wherein the base 91 of the groove 92 is made to follow a curved path rather than a relatively straight line, preferably the angle between the sides of the groove 92 being ninety degrees and the curvature interlocking semicircles drawn about aligned points. Thus the total distance encompassed by the line will be twice the width covered by a straight groove. Due to the unusual brilliancy of my sign, the legend when illuminated gives the effect of a straight, uniformly broad line, the waviness being undetectable except when the sign is in an unilluminated condition.

In operation it will be found that the legend of my sign is illuminated with a brilliancy approaching that attained by neon signs or the like and that the intensity of illumination throughout the legend is remarkably uniform. Since the diameter of the lamp at least approximates the thickness of the sheet, and since the sheets are disposed on opposite sides of the lamp, it may be seen that substantially all of the light is usefully employed and that the cost of operation will therefore be minor. The light rays entering each of the plates are in effect fanned

out parallel to the plane of the plate, some of the rays being intercepted by incicia and other of the rays striking the reflective edges on the plate. These rays are reflected back into the sign and are eventually intercepted by some portion of the legend. The combined diffracting and reflecting of the light disperses the rays uniformly throughout the sign and provides very even illumination of the legend.

It will of course be obvious to those skilled in the art that the color effects of my sign are practically unlimited and can be varied at will by arrangement of colored films between the source of light and the sign and that blends of colors may be obtained by the use of strips of different colors applied to either edge of the same plate and interposed between the plate and the source of illumination. Many undescribed permutations and combinations may thus be obtained without departure from my invention and I do not therefore wish to limit myself to the precise details herein disclosed except insofar as defined in the appended claim.

I claim:

25 A sign comprising a plate of transparent light-transmitting plastic having a legend engraved thereon, the cross sectional configuration of said legend including a relatively deep central groove portion extending inwardly from the face of the plate a distance not greater than one-half the thickness of the plate and shallow marginal groove portions also extending inwardly from the same face of the plate and bounding the said central groove portion, whereby the clarity of the legend, when brilliantly illuminated, is increased.
